ABSTRACT: Apparatus for pickling a plurality of steel wires includes an acid reservoir connected to an acid-recirculating tank with a tray above the tank for receiving the acid. The tank is covered over the majority of its area, but has at least one raised section extending above the tank cover. The tray is also covered and has an overflow weir at each end of the tray to provide a narrow slot through which wires pass. Means are provided for circulating the acid from the tank to the tray, over the top of the weirs, and back to the tank. Means are provided for transferring acid from the reservoir to the tank when the level of the acid falls to a predetermined level below the top of the raised sections but above the tank cover.

SHEET 2 OF 2

WIRE-PICKLING APPARATUS

This invention relates to apparatus for treating a moving elongated workpiece with a liquid vaporizable at the treating temperature, and more particularly to apparatus for pickling steel wire in a multiple-strand operation.

This is most commonly done at present by having one or more open tanks positioned in series, or one or more open tank-tray assemblies positioned in series. In the first case, the wire strands are greatly in the pickling acid by rolls located in each tank. In the latter case, there is straight line travel through the tray which is filled with acid circulated from the lower tank to the upper tray. Since the acid is vaporizable at the temperature at which it is used, it has been found that approximately 50 percent of the total acid consumed is the result of vaporization. This is also true of other processes in which the treating liquid is vaporizable.

It is therefore an object of my invention to provide apparatus for treating a moving workpiece by means of a vaporizable liquid in which the surface area of the bath opposed to the atmosphere is greatly reduced.

Another object is to provide such apparatus which reduces the heat required to maintain a desired bath temperature and also reduces the escape of corrosive vapors into the atmosphere.

These and other objects will become more apparent after referring to the following specification and attached drawings, in which:

FIG. 1 is a longitudinal side view of a tank-tray assembly incorporating my invention; and

FIG. 2 is an end view of the assembly of FIG. 1.

Referring more particularly to the drawings, reference numeral 2 indicates a pickling tray having a cover 4. As shown, the cover is made of two L-shaped longitudinal sections 4a and 4b with their adjacent sides spaced apart with one leg of each section extending upwardly from the adjacent sides of the sections to form a longitudinal passageway 6 having a width slightly greater than the diameter of wires W being pickled.

The wires W are fed from payoff reels 8 and drawn through the pickling tray by means of takeup blocks 10. A weir plate 12 forms the exit end of the tray and extends to within a short distance of the horizontal portion of the tray cover 4 to provide a slot 13. The top of the weir plate 12 has a plurality of spaced semicircular grooves 14 therein for individually receiving the wires W. An acid overflow chute 16 is attached to the weir plate 12. A similar weir plate 18 and overflow chute 20 are provided at the entry end of the tray 2. The tray 2 is supported above an acid-recirculating tank 22 which has raised sections 24 and 26 at the exit and entry ends thereof. Except for these raised sections, the top of the tank is covered by a substantially horizontal cover 28.

A pump 30 driven by a motor 32 delivers acid from the tank 22 through piping 34 to the tray 2. An acid makeup reservoir 36 is mounted adjacent the tank 22 and acid is delivered to tank 22 through piping 38 by means of a pump 40 driven by a motor 42 controlled by a standard motor control 44. Power for the motor 42 is obtained from powerlines L1 and L2 connected to motor control 44. A switch 46 in lines L1, L2 is actuated through linkage 47 by means of a float 48 mounted in the raised section 24 of tank 22. It will be seen that the chutes 16 and 20 discharge into the raised portions 24 and 26, respectively. An acid vapor condenser 50 is preferably provided for the reservoir 36 and the acid in the tank 22 is preferably maintained at a temperature of approximately 160° F. by means of steam-heated coils 52.

In operation, the wires W are individually strung up by being fed down through the slot 6 and along the horizontal slot 13 to a position in the selected groove 14 and then attached to takeup block 10. The pump 40 transfers acid from the reservoir 36 to the tank 22 and the pump 30 transfers the acid from the tank 22 to the tray 2 after the acid in the tank 22 has risen a considerable distance into the raised sections 24 and 26. At this time, the float 48 will cause the switch 46 to open and thus stop transfer of the acid from reservoir 36 to the tank 22.

Since the tray 2 and tank 22 are completely filled with acid except for the end sections 24 and 26, the only exposure of the acid to the atmosphere is in end sections 24 and 26 and the trough 16. The end sections 24 and 26 may also be partially

5 covered by means of the covers 54 and 56 if desired. The acid is kept in circulation by means of pump 30 and returns to the tank 22 by overflowing the weirs 12 and 18. When the level of the acid in the raised portion 24 falls to a predetermined level above the top of cover 28, the float 48 will cause switch 46 to close thus energizing motor 42 and causing the pump 40 to deliver additional acid to the tank 22. After the acid raises in the end section 24 to a predetermined level, the float 48 will cause switch 46 to open and stop transfer of the acid.

15 A typical tank tray assembly consists of a tank 16 feet long and 30 inches wide and a tray 14 feet long and 30 inches wide. Compared to the 75 square feet surface area of such an assembly used prior to my invention, the present invention has only a maximum of 5½ square feet surface area exposed to the atmosphere. This results in approximately 93 percent less area exposed to the atmosphere with a comparable reduction in vapor loss.

20 While one embodiment of my invention has been shown and described, it will be apparent that other adaptations and modifications may be made without departing from the scope of the following claims.

I claim:

1. Apparatus for treating a moving elongated workpiece with a liquid vaporizable at the treating temperature comprising 30 a liquid reservoir, a liquid-recirculating tank, generally horizontal means covering the majority of the top of said tank, said tank having a raised section extending above said tank-covering means, a connection between said reservoir and tank, means operable when the liquid in said tank is at a predetermined level below the top of said raised section and above the tank covering means to transfer liquid from said reservoir through said connection to said tank, a tray above said tank for receiving said liquid, generally horizontal tray-covering means covering the majority of the top of said tray, means for circulating said liquid from said tank to substantially fill said tray and back to said tank, and means for moving said workpiece longitudinally through said tray.

40 2. Apparatus according to claim 1 in which said raised section is at one end of said tank; and said circulating means includes liquid overflow means at the end of said tray adjacent said raised section, and means directing liquid from said overflow means to said raised section.

45 3. Apparatus according to claim 2 in which said workpiece is a steel wire, and means are provided for moving a plurality of steel wires in generally parallel relationship through said tray.

50 4. Apparatus according to claim 3 in which said overflow means includes a weir plate forming the end of said tray and extending to within a short distance below said tray cover.

55 5. Apparatus according to claim 4 including a second raised section in said tank at the end opposite the first raised section, and a second weir plate forming the end of said tray opposite the first weir plate, said second weir plate extending to within a short distance below said tray cover.

60 6. Apparatus according to claim 5 including means for directing liquid overflowing said second weir plate to said second raised section.

65 7. Apparatus according to claim 6 in which said tray cover includes two longitudinal L-shaped sections having their adjacent sides spaced apart with one leg of each L-shaped section extending upwardly from the adjacent sides of said sections to form a longitudinal passageway having a width slightly greater than the diameter of said wires.

70 8. Apparatus according to claim 7 in which each of said weir plates has spaced apart grooves in the top surface thereof for individually receiving said wires.

9. Apparatus according to claim 3 in which said tray cover includes two longitudinal L-shaped sections having their adjacent sides spaced apart with one leg of each L-shaped sec-

tion extending upwardly from the adjacent sides of said sections to form a longitudinal passageway having a width slightly greater than the diameter of said wires.

10. Apparatus according to claim 9 in which said overflow means includes a weir plate forming the end of said tray and extending to within a short distance below said tray cover.
